UNITED STATES PATENT OFFICE

134,413

DESIGN FOR AN OPHTHALMIC MOUNTING

Joy P. Miller, Ashland, Nebr.

Application July 14, 1942, Serial No. 107,538

Term of patent 14 years

To all whom it may concern:

Be it known that I, Joy P. Miller, a citizen of the United States, residing at Ashland, in the county of Saunders and State of Nebraska, have invented a new, original, and ornamental Design for an Ophthalmic Mounting, of which the following is a specification, reference being had to the accompanying drawing, forming part thereof.

Fig. 1, is an enlarged fragmentary front perspective view of an ophthalmic mounting showing the dominant feature of my design by full lines as applied to the lens holding rim of a conventional frame type mounting illustrated by dotted lines.

Fig. 2, is a complete plan view of the conventional mounting shown in Fig. 1, with the characteristic features of the design in full lines.

Fig. 3, is a view similar to Fig. 1, but looking at it from the rear.

The dominant feature of the present design is shown in solid lines and broadly comprises a relatively long, slender, substantially cylindrical hinge barrel arrangement rigid with the lens supporting rim and located with its axis upright and substantially parallel with and to the rear of the plane of the lens rim, and a temple having a forward end portion curving outwardly and rearwardly from the side of the lens rim and provided at its concave side with an offset semi-cylindrical hinge barrel portion resting upon and blending with the upper portion of the hinge barrel arrangement of the lens rim.

I claim:

The ornamental design for an ophthalmic mounting, substantially as shown and described.

JOY P. MILLER.
